DOUBLE GLAZING

Ernest E. Phillips, Leaside, Ontario, and Walter R. Packman, Toronto, Ontario, Canada; said Packman assignor to said Phillips

Application April 12, 1939, Serial No. 267,454

3 Claims. (Cl. 20—56.5)

The principal objects of this invention are to provide a simple but efficient double glazing attachment which may be easily applied without alteration in the standard sash formation and which will be tightly held in place in a manner which will permit the ready removal or replacement thereof.

The principal features of the invention reside in the novel construction of the double glazing frame and a special resilient retaining means for securement to the sash whereby the double glazing frame is resiliently urged into snug sealing engagement with the sash but is capable of ready removal by flexing of the resilient retaining means.

In the drawing Figure 1 is a fragmentary cross section through a portion of a sash showing a preferred form of the present invention applied thereto.

Figure 2 is a view similar to Figure 1 showing a modification of the present invention.

Figure 3 is a fragmentary corner view of a double glazing frame such as shown in Figures 1 and 2, the frame portion being broken away to disclose the underlying resilient retaining means.

Many forms of structures have been devised in connection with double glazing of windows but these in many cases are of a complicated nature or require sashes of special cross section or the provision of recesses.

The present invention has been devised to eliminate these objections and to enable the mounting of a double glazing frame directly on any standard window sash, and in the preferred form of the invention illustrated in Figures 1 and 3 a special retaining member 1 is provided which preferably comprises a strip of resilient metal of angle shaped cross section having a flange 2 adapted to flatly overlie the inner face 3 of the sash 4 with or without a sealing strip 5 therebetween.

The other flange portion 6 extends perpendicular to the face 3 of the sash and is here shown provided with an inwardly rolled or beaded extremity 7.

The strips 1 are preferably placed in a rectangular arrangement presenting mitred corner joints 8 and with the inner edge of the flange 5 in register with an edge 9 of the sash to provide for accurate positioning.

A double glazing frame 10 is shown in Figure 1 as formed of a strip of metal, the edge portions of which are doubled back upon themselves and turned laterally to form a channel 11 within

which the edges of the secondary glass 12 are sealed.

The intermediate portion of the strip is bent to provide a tapering or bevelled area 13, which, when the frame is pressed into position, will engage the beaded portion 7 of the spring-retaining means and spread these sufficiently to allow the shoulder portion 14 to pass therebeyond. The portion of the strip on the other side of the shoulder 14 is channelled to provide a sloping wedge surface 15 which is adapted to co-operate with the beaded portion 7 of the retaining means so that the resilient inward pressure of the latter on the sloping wedge surfaces will exert an inward pressure on the frame 10 tending to urge the same into snug non-rattling relation to the sash, and a sealing strip of felt or the like 16 may be arranged between the inner portion of the frame 10 and the flange 5 to be retained under sealing compression by the resilient wedging engagement referred to.

The frame-forming strip is flared outwardly to overhang the beaded portion 7 and to extend beyond the flange 6 and the arrangement is such that a space 17 will be provided between the overhanging portion and the beaded portion 7 as illustrated in Figure 1. This provides an advantageous arrangement for the insertion of a prying tool 18. With this arrangement a gentle pull on the inserted member 18 will exert an effective prying action on the frame while a constricting force will be applied to the beaded portion 7 as well as a spreading action on the flanges 6, providing for the very easy removal of the frame.

In the modification shown in Figure 2 the frame 10' is shown formed of a strip of extruded metal having the tapered surface 13' and wedging surface 15' arranged to cooperate with the resilient beaded portion 7' as defined in connection with the corresponding surfaces 13 and 15 of Figure 1.

What we claim as our invention is:

1. The combination with a standard sash, having its innermost surface disposed in a flat plane, of a double glazing frame to be applied flat over said innermost sash surface and formed with a sloping wedging surface about the perimeter, and resilient retaining members formed of strips of spring metal of substantial right-angled flanged form disposed in a rectangular frame formation and having one flange portion secured flat to the said innermost sash surface in such relation as to be overlapped and concealed by the said frame and having the other

flange portion extending substantially perpendicular to said innermost plane forming a resilient frame continuously embracing the perimeter of said double glazing frame in resilient pressure-holding relation in contact with said sloping surfaces.

2. The combination with a standard sash having its innermost surface disposed in a flat plane, of a double glazing frame for application over said innermost sash surface, said frame being formed with a wedging surface extending about the perimeter, and strips of spring metal having flange portions for attachment to the said innermost surface of the sash in underlying relation to the said frame and having inturned portions for resilient wedging engagement with said wedge surfaces, said frame presenting rigid flange portions overhanging and spaced from the inturned portions of said spring strips, and adapted to form a space for the reception of a frame-removing instrument whereby a prying action may be exerted between said overhanging flanges and the inturned portions of said spring strips to remove the frame without marring of the inner surface of the sash.

3. The combination with a standard sash having its innermost surface disposed in a flat plane, of a double glazing frame formed to overlap said innermost plane surface of the sash and presenting a locking groove about the perimeter spaced inwardly from said innermost sash surface, and spring-retaining members secured to the sash and having beaded portions spaced inwardly beyond said innermost sash surface 10 a distance slightly less than the inward spacing of said frame groove to engage the outermost wall of said groove in pronounced wedging action to thereby retain the frame in pressure engagement with the sash, said beaded portions being 15 of resilient form confined within the plane of the double glazing frame and return-bent toward the latter and outwardly to substantial circular form with the free end portion of the resilient bead presenting the major resilient wedging engagement with the groove wall whereby to facilitate placing and removal of the double glazing frame.
